Handcrafted Ergonomic Electric Guitar, image post date Sep. 30, 2013, site visited Mar. 20, 2016, (online), <<https://connorlukas19.wordpress.com/2013/09/30/handcrafted-ergonomic-electric-guitar/>>.*

Primary Examiner — Kevin Rudzinski*Assistant Examiner* — Sean D Lough(74) Attorney, Agent, or Firm — Pearl Cohen Zedek Latzer Baratz LLP(57) CLAIM

The ornamental design for an ergonomic guitar body, as shown and described.

DESCRIPTION

FIG. 1 is a perspective view of the ergonomic guitar body;
 FIG. 2 is a rear perspective view thereof;
 FIG. 3 is a front elevation view thereof;
 FIG. 4 is a back elevation view thereof;
 FIG. 5 is a right elevation view thereof;
 FIG. 6 is a left elevation view thereof;
 FIG. 7 is a top plan view thereof; and,
 FIG. 8 is a bottom plan view thereof.

1 Claim, 3 Drawing Sheets(56)
